ADJUSTABLE LAMP SUPPORT

Karl Harz, Ridgewood, N. J.

Application November 12, 1935, Serial No. 49,393

7 Claims. (Cl. 248—122)

This invention relates to that classification of structures embodying electric lamps in general, but has more explicit reference to a support or stand possessed of combined utilitarian and ornamental developments.

In reducing the preferred embodiment of the invention to practice I have found it expedient and practicable to adopt and use a double unit or two part supporting structure, this being characterized in an arrangement which has as one of its parts an ingenious stand characterized by a unique tripod base, the stand including an upright designed intermediate its upper and lower ends to pivotally support a rotative fixture serving as a carrier for a suitable electric lamp or the source of illumination.

In keeping with a desire to provide a practical and systematic coordination of features, so as to in turn provide requisite symmetry of appearance and dependable structure of balance and stability, I have fashioned and connected the respective parts so that the structure, as a whole, is in the nature of a cruciform oddity.

Indicated along more explicit lines, this apparent innovation is characterized by the relatively stationary base and stand and the swingably mounted lamp carrier fixture having their main or central portion pivotally joined together in intersecting cruciform relationship, and their free end portions laterally directed to resemble what may be designated as a Swastika.

Other features and advantages will become more readily apparent from the following description and the accompanying illustrative drawings.

In the drawings, wherein like numerals are employed to designate like details or parts throughout the views:—

Figure 1 is an elevational view which may be considered as a front view with the parts in cruciform relationship.

Figure 2 is a horizontal section through the lower portion of the structure taken approximately on the plane of the line 2—2 of Figure 1.

Figure 3 is a simple horizontal sectional view taken approximately on the plane of the line 3—3 of Figure 1.

Figure 4 is a fragmentary edge view of the portion of the stand or upright which serves as a mounting or bearing for the oscillatory lamp supporting fixture.

Figure 5 is a detailed sectional view through the socket adapter arm forming the upstanding part of the oscillatory carrier fixture.

As before indicated, the structural assemblage

is identified as composed primarily of two complementary units, the unit 6 constituting the stand or pedestal and the unit 7 functioning as a swingable or oscillatory lamp adapter fixture. Both of these parts 6 and 7 are essentially made up of flat straps or strips of metal of appropriate malleable or bendable character. That is to say, each part includes as a major portion thereof a bar which has its end portions bent in opposite direction to define what may be conveniently referred to as a straight S-shaped part. It is believed advisable, however, to refer to these similarly shaped parts by distinguishing numerals. The part 6 therefore comprises a vertical member which constitutes an upright 8. The lower end of this is twisted upon itself as at 9 and then directed laterally in one direction as at 10 to form one horizontal portion of the tripod base. There are additional companion members 10a of similar design these being attached at their inner end portions 11 to the lower part of the upright 8. The outer ends of these parts 10 and 10a bent laterally upon itself as at 12 to form a vertical foot 13. The extreme lower ends of these feet 13 are fashioned with oppositely bent rests or toes 14. The upper end of the strap 8 is bent upon itself as indicated at 15 and extended laterally to define what may be conveniently referred to as a handle 16. This handle extends in a direction opposite to the first named end 10. These features 8, 10 and 16 form the aforementioned S-shaped member.

Referring now to Figure 4 it is to be noted that the central portion of the upright 8 is bent to form a U-shaped part which may be functionally described as a stop in that it limits the swinging movement of the carrier 7 in opposite direction. Connected with the open portion of this stop 17 is a vertical journal pin 18 appropriately riveted in place. This is utilized to accommodate the bearing means of the central portion of the part 7.

Taking up in detail the part 7, it comprises, as before stated, a main strap or body portion 19 of a length substantially equal to the part 8. The extreme central portion thereof is bent upon itself as indicated at 20 to form one-half of the bearing. This cooperates with the similarly bent bearing clip 21 which is secured to the opposite side and these features 20 and 21 rotatably embrace the pin 18 to provide the desired hinging or pivotal action.

Noting now the left-hand end of the arm 19 it is to be observed that it is bent upon itself as indicated at 22 and then upwardly as at 23, the extreme upper end being bifurcated and the

furcations being indicated at 24. The furcations serve to accommodate the rigidly attached or mounted short pipe section 25 whose upright is screw threaded to accommodate the lamp socket 26. In fact any suitable type of bulb or shade may be employed to make up the complete lamp. The features 23, 24 and 25 are as described the adaptation for the socket 26. The opposite end of the strap 19 is bent upon itself as at 27 and 10 directly downwardly to form a rightangularly disposed pendant 28. These features 23 and 28 are commensurate in length to the aforementioned features 10 and 16 to serve primarily as a matter of symmetrical balance in appearance. 15 Part 16 serves as a lifting and carrying handle for the whole structure and part 28 is sometimes used as a turning handle for the swingable carrier unit 7.

As before indicated the structure as a whole 20 is representative of a cross of the type referred to as a Swastika. While this is incidental it is nevertheless a feature of appearance which gives the requisite oddity of appearance desirable for sake of attraction and appeal. Visualizing the 25 structure without the laterally bent end portions and reviewing the major or center portions it is of general cruciform design. These developments are necessarily for purpose of design but are functionally intended to promote stability and 30 balance and are therefore primarily utilitarian in character.

Novelty is thought to reside in the adoption and use of the unit 6 characterized by the tripod base and the stand or upright 8 having a lateral handle 16 at its top, the central portion of the stand being fashioned to provide a bearing and stop means for the centrally mounted carrier unit 7. The carrier unit 7 is believed unique in that it may be swung through a limited arch to position 35 the lamp (not shown) at a most advantageous position in relation to the base for reading purposes. In other words by grasping the handle 28, which may be in convenient reach of a reading chair, the lamp may be brought around 40 over a book or other object and conveniently utilized or it may be swung to an out-of-the-way position as desired.

Manifestly, these features have been carefully selected and mechanically coordinated to provide 50 an assemblage which, it is believed, may be satisfactorily endorsed commercially and otherwise as an innovation in this line of endeavor.

It is thought that persons skilled in the art 55 to which the invention relates will be able to obtain a clear understanding of the invention after considering the description in connection with the drawings. Therefore, a more lengthy description is regarded as unnecessary.

Minor changes in shape, size, and rearrangement 60 of details coming within the field of invention claimed may be resorted to in actual practice, if desired.

Having thus described the invention, what I claim is:—

65 1. As a component unit of the structural assemblage of the class described, a flat metal strap having its upper end bent upon itself and extended at rightangles to form an ornamental handle, the lower end of said strap being bent 70 upon itself and directed at right angles in a direction opposite said handle, the outer end of said last named portion of the strap being bent laterally downward to form a floor contacting foot, and a pair of diverging complementary members similar to the rightangularly bent lower

end of said strap, said members being of duplicate construction and having their outer ends bent down to form additional supporting feet and the intermediate portion of the strap proper being of U-shaped formation and equipped with an 5 associated fixedly mounted pin serving as a journal.

2. As a component unit of structural assemblage of the class described, a lamp carrier and adapter fixture comprising an elongated flat 10 strip of metal provided intermediate its ends with an attaching and hinging bearing, the strip being bent upon itself and extended at right-angles to the body portion at one end thereof to provide a depending operating handle, the opposite end of the strip being bent upon itself and extended at rightangles in a direction opposite 15 said handle and fashioned at its free end to accommodate a lamp socket and cord.

3. In a structure of the class described, a relatively stationary stand including a base having a vertical standard, a lamp carrier unit comprising a flat strap of metal hingedly attached intermediate its ends to the central portion of said standard, one end of said strap being bent laterally downward at rightangles to form a turning handle, the opposite end being extended in a direction opposite to said handle and bent at rightangles to extend vertically upward, the extreme upper end of said last named portion being 30 bifurcated and fitted with a screw-threaded sleeve to accommodate a socket and complementary electric cord in the manner and for the purposes described.

4. In a lamp construction of the class described, a relatively stationary portable stand adapted to be bodily lifted and transported from place to place including a base, a vertical standard rising therefrom and having a handle at its top, the intermediate portion of said standard 40 being provided with a hinge pin, and a complementary lamp carrier and adapter fixture cooperative with said stand and including an elongated flat strip of metal provided intermediate its ends with an attaching and hinging bearing connectible with said pin, said strip being bent upon itself and extended at right angles to the body portion at one end thereof to provide a depending operating handle, the opposite end of the strip being bent upon itself and extended 45 at right angles in the direction opposite to said handle and fashioned at its free end to accommodate a lamp socket and cord.

5. A portable table lamp construction including a stand provided with a base, an upright rising vertically from said base, said upright being provided at its upper end with a lifting and carrying handle, a relatively movable lamp carrier and adapter fixture comprising a horizontally disposed member intersecting and 55 pivotally attached intermediate its ends to the intermediate portion of said standard, said horizontal portion being provided at one end with a depending handle terminating in close proximity to the base and disposed beneath said first-named handle, the opposite end of said horizontal member extending upwardly to a point substantially even with the upper end of the standard and having means to accommodate 60 a lamp.

6. A lamp frame construction of the class described comprising a stand having a base, an upright rising vertically from said base, said upright being formed intermediate its ends with a substantially U-shaped portion, a supporting 75

and hinge pin mounted on said standard and bridging the open side of said U-shaped portion, and a lamp carrier and adapter fixture including a horizontal portion disposed at right angles to and intersecting said upright, and formed intermediate its ends with an attaching bearing connected with said pin, said bearing being associated with said U-shaped portion whereby to permit the U-shaped portion to function as a stop to limit the swinging movement of the horizontal portion in the opposite directions.

7. In a lamp construction of the class described, a relatively stationary portable stand including a base, an upright attached thereto and rising vertically therefrom, said upright in-

cluding a flat strap of metal, the upper end of said strap being bent laterally to form a horizontally disposed lifting and carrying handle, and a carrier fixture formed from a single strap of metal and including a horizontal portion pivotally attached intermediate its ends to the intermediate portion of said first-mentioned stop, such carrier strap having one end bent down to form an operating handle, this being located directly beneath the lifting and carrying handle and disposed at right angles thereto, the opposite end of the carrier strap being bent laterally up and terminating on a plane substantially even with the handle on said upright. 5

KARL HARZ. 15
